(57) **CLAIM**

The ornamental design for a water float, as shown and described.

DESCRIPTION

The file of this patent contains at least one photograph executed in color. Copies of this patent with color photograph(s) will be provided by the Office upon request and payment of the necessary fee.

FIG. 1 is a front perspective view of a water float showing, in particular, the ornamental design thereof.

FIG. 2 is a front end view of the water float of FIG. 1.

FIG. 3 is a rear end view of the water float of FIG. 1.

FIG. 4 is a right side view of the water float of FIG. 1.

FIG. 5 is a left side view of the water float of FIG. 1; and, FIG. 6 is a top plan view of the water float of FIG. 1. The bottom of the water float is flat and devoid of surface ornamentation.
